APPARATUS FOR WASHING AND CEMENT-
ING OIL WELLS

James E. Terrill, Joinerville, Tex.

Application February 4, 1938, Serial No. 188,752

9 Claims. (Cl. 166—1)

This invention relates to a method of and apparatus for washing and cementing oil wells.

The invention has for its object to provide for a clean hole before the cement is run into the well.

The invention has for its further object to insure for the cleaning medium being directed against the bottom and up along the sides of the well to provide a clean hole; and for the cement being directed against the bottom and up along the sides of the well to insure for the plugging of a definite amount of the depth of the well.

The invention has for its further object to provide an annular imperforate sleeve or liner constituting a director for the cleaning medium and cement and further for coating with the cement to provide a plug anchored to the bottom and to the sides of the well below the oil stratum.

A further object of the invention resides in the utilization of a director for the purpose aforesaid having connected therewith a valve controlled cement arresting means to prevent the backing up of the cement when the latter coats with the director to provide the plug.

A further object of the invention resides in the combining with the director and arresting means aforesaid a perforated sleeve forming a by-pass for the cleaning medium when flowing in an outward direction during the washing operation to clean the hole, and further acting for discharging the cleaning medium into the well when such medium is employed to remove surplus cement which has been supplied to coat with the director to form the plug at the bottom of the well for sealing the water stratum.

A further object of the invention resides in the utilization of a tubing for selectively supplying the cleaning medium and cement slurry directly into and through the director aforesaid and also for supplying the cleaning medium directly into the perforated sleeve for passage therefrom into the hole.

A further object of the invention resides in the means whereby all sand, rotary mud and oil may be removed through the well casing to insure a clean hole before the cement is run.

Embodying the objects aforesaid and to others which may hereinafter appear, the invention consists of a method of and an apparatus for washing and cementing oil wells as hereinafter set forth, but it is to be understood that changes, variations and modifications may be resorted to which fall within the scope of the invention as claimed.

In the drawings:

Figure 1 illustrates, in vertical section the simulation of an oil well showing the adaptation therewith of an apparatus for carrying out the method in accordance with this invention. The apparatus is shown partly in vertical section.

Figure 2 is a vertical sectional view of the apparatus broken away and upon an enlarged scale.

Figure 3 is a fragmentary view partly in elevation and vertical section of elements of the apparatus disassembled.

Figure 4 is a section on line 4—4, Figure 3.

Figure 5 is a section on line 5—5, Figure 2.

Figure 6 is a section on line 6—6, Figure 2.

Figure 7 is a side elevation of a modified form and

Figure 8 is a side elevation of another modified form.

With reference to Figure 1, an oil well is indicated at 1, into which depends for a portion of its depth a casing string 8. Below the latter 20 is the oil stratum 9 and the water stratum 10. The bottom and sides of the wall are indicated at 11, 12 respectively. The foregoing is illustrated by way of example so as to show the adaptation with an oil well of a washing and 25 cementing apparatus in accordance with this invention.

The apparatus includes a coupler element 13 formed of an annular sleeve-like body 14 and an internal integral web 15 which constitutes an 30 abutment for arresting back flow of the cement from the inner or lower liner to be referred to. The inner face of body 14 consists of an intermediate portion 16, an upper end portion 17 and a lower end portion 18. The intermediate 35 portion 16 is of uniform diameter and the web 15 is integral with the intermediate portion 16 adjacent one side of its transverse median. The upper end portion 17 gradually increases in internal diameter from the upper end of the intermediate portion 16 to the upper end 19 of body 14 and is formed throughout with threads. The lower end portion 18 gradually increases in internal diameter from the lower end of the intermediate portion 16 to the lower end 20 of body 14 45 and is threaded throughout.

The web 15 merges into a sleeve 21 arranged in coaxial relation with respect to body 14. The sleeve 21 is of materially less length and diameter than the body 14. The web 15 merges 50 into the sleeve 21 at a point in close proximity to the lower end of the latter. The inner face of sleeve 21, at its transverse median, is formed with an annular flange 22 forming superposed shoulders 23, 24. The upper portion 25 of the inner 55

face of sleeve 21 increases in internal diameter from the shoulder 23 to the upper end 26 of the sleeve and is formed with left hand threads throughout. The lower portion 27 of the inner face of sleeve 21 increases in internal diameter from the shoulder 24 to the lower end 28 of the sleeve and is threaded throughout. The threads on portion 27 may be right or left hand threads and if left hand threads, the element 13 is reversible.

The apparatus includes a combined water and cement director element 29 in the form of a sleeve of the desired length with open ends and having its body imperforate throughout. The end terminal portion 31 of sleeve 30 has its outer periphery tapered and threaded. The portion 31 extends into the body 14 and its threads engage with the threaded inner face portion 18 of the body 14 whereby elements 13 and 29 are connected together. The outer diameter of element 29 is less than the outer diameter of element 13. The element 29 may be termed a blank liner and is open at each end.

The apparatus includes a check valve unit 32 which is suspended from coupler element 13 and extends into the director element 29. The unit 32 consists of a tubular member 33 open at each end and having a reduced upper end part 34, an enlarged lower end part 35 and a tapered intermediate part 36 which merges into the lower end of part 34 and into the upper end of part 35. The part 36 constitutes a seat for a ball valve 37 loosely arranged within the part 35. Extending diametrically of and anchored to the outer end of part 35 is a valve stop or confiner 38. The end part 34 has a portion of the length of its outer periphery tapered and threaded, as at 39, for engagement with the portion 27 of the inner face of sleeve 21 of the element 13 whereby element 32 is connected to, suspended from and disposed in coaxial relation with respect to element 13.

The apparatus includes an annular perforated liner 40 in the form of an elongated sleeve which has the outer periphery of the end terminal portion 41 thereof tapered and threaded. The portion 41 extends into the element 13 and engages the tapered threaded portion 17 of the inner face of element 13 thereby connecting liner 40 and element 13 together. The liner 40 extends into the lower portion of casing 8. Connected to the upper end of the casing 8 is a removable head structure 44 provided with a valve controlled water or cleaning medium outlet pipe 45 and a valved water and cement conducting line 46 which leads from a water supply and a cement supply pump not shown.

The apparatus includes a conductor element 47 common to the washing medium and the cement slurry. The element 47 is in the form of an elongated tube attached to the head structure 44 for communication with the line 46. The lower end terminal portion 48 of the element 47 has its outer periphery tapered and formed with left hand threads for coaction with the threaded portion 25 of the inner face of sleeve 21 whereby the conductor element 47 is detachably connected to element 13.

When the apparatus is employed to carry out the first and second steps of the method, the conductor element 47 is connected to the sleeve 21 of the coupler element 13 for the purpose of supplying, first, water through sleeve 21 and valve unit 32 and then into and through director element 29 into the well at the bottom thereof,

and for the purpose of supplying, secondly, cement slurry through sleeve 21, valve unit 32 and into and through director element 29 into the well at the bottom thereof. When the apparatus is employed to carry out the third step of the method, the conductor element 47 is detached from the sleeve 21 and directly discharges water into the liner 40.

As to the method: Water is pumped into the conductor or tubing 47 down through the coupler element 13, valve unit 32 and the director element 29 to the bottom of the well and backs up between the director element 29 and wall of the well, entering liner 40 through the perforations of the latter, and also up through oil string 15 casing 8 to the surface of the ground, washing with it all sand, rotary mud and oil, insuring a clean hole before the cement is run. In the present method of using only the tubing for washing the well out, it is impossible to wash the 20 side walls and bottom clean.

After washing, the required amount of cement slurry is pumped into the conductor element 47 and followed up with water to force all of the cement out of the conductor element 47 into the 25 bottom of the hole. After pressure has been applied to the cement, the conductor element 47 is backed off of sleeve 21, raised and more water pumped through element 47 to wash out the 30 excess cement in the event there was a miscalculation in the amount of cement needed, pressure is again applied and let set until cement has become hard.

With respect to the blank liner 29, it does not only direct the water, during the washing to 35 clean out the bottom and direct the water along the sides of the well, but insures a definite amount of the depth of the well to be plugged off. Even where there is an insufficient amount of cement, it will still make a solid plug if there is 40 sufficient cement to fill the lower end of such liner, as the amount of water which follows the cement up is measured to displace all cement in the conductor element 47, sleeve 21 and the valve unit 32.

The element 13 not only acts as a coupler, but further functions as a retainer for the cement. The valve unit 32, carried by the coupler element 13 acts, after the pressure has been applied to the cement and the conductor element 47 disconnected from sleeve 21 to wash out surplus cement, to prevent the cement in directing element 29 from backing up into the sleeve 21.

After the method has been completed, the element 47 is removed, but the elements 13, 29, 33 and 40 in their secured together position are anchored in the bottom of the well.

The elements 13, 29, 33, 40 and 47 will be hereinafter referred to respectively in the claims as an annular body formed intermediate its ends 60 with an internal abutment carrying a sleeve, an imperforate liner, a valve structure, a perforated liner, and a conduit for and common to a washing and a cementing medium.

The elements 13, 29, 33, 40 will also be hereinafter referred to in the claims as an anchored controllable directing unit common to the washing and sealing medium and with the unit consisting of an upper or outer perforated liner, a lower imperforate liner, a combined coupling and 70 abutment element interposed between and connecting the liners together, and means for controlling communication between said liners. The directing unit is controlled by the conductor 47. The directing unit is anchored by the directed 75

sealing or cementing medium acting to seal the bottom of the wall and the water stratum.

With reference to Figure 7 the form shown thereby will be the same as that shown in Figures 5 1 and 2, with this exception that there is substituted for the perforated liner 40 an imperforate liner 49. In Figure 7 the coupler element for the liners 49, 50 is designated 51 and the conduit or tube common to a washing and a cement medium at 52.

The liners 49, 50 and the coupler element 51 are permanently connected together to form a unit. The conduit 52 extends through liner 49 and opens into and is detachably connected to element 15 51. The unit is lowered into the well to a point in proximity to the bottom of the latter by the conduit 52. Water is then pumped into the latter and conducted through the coupler element 51 and the liner 50 to the bottom of the well and 20 back up between liner 50, element 51 and liner 49, entering well casing and back to the surface. After enough water has been pumped to wash the well walls clean, then cement is pumped into the conduit 52 following the same course as the 25 water to a point at the lower portion of the well casing. The cement will form a solid wall within the liner 50 and a wall between the well walls and the liners 49, 50. Conduit 52 is then detached and water supplied to liner 49. The water re- 30 bounds against the coupler element 51 and passes up washing out all excess cement. After the cement has had time to set, the conduit 52 is removed and a perforating gun is run into the wall and perforates liner 49 at any point above ele- 35 ment 51.

It is to be understood that the unit shown in Figure 7, consisting of the liners 49, 50 and the coupler element 51, may be suspended from any well known type of hanger capable of being positioned respectively to provide for the outflow of 40 the washing medium through the well casing and to arrest the cement passing upwardly through the casing from the upper end of liner 49. With respect to this arrangement the hanger, not shown, is to be connected to liner 49.

In the modified form shown in Figure 8 it discloses the upper liner indicated at 52a and which is imperforate and a coupler element indicated at 53 attached to the lower end of the liner 52a. The coupler element 53 is of the same form and construction as elements 13, 51 and includes the valve unit shown in Figure 2. The lower liner is omitted. The liner 52a is connected to a hanger or packer 54 which is employed to anchor liner 52a and the coupler element 53 in the lower portion of the well. After the well has been filled to the desired extent with cement, which is prevented from backing up into the liner 52a by the valve unit on the coupler element 53, the liner 60 52 can be perforated by gunning without having to drill cement therefrom.

What I claim is:

1. In an apparatus for the purpose set forth, an upstanding annular body open at each end 65 and formed intermediate its ends with an axially apertured horizontally disposed internal abutment provided with an upstanding sleeve registering with said aperture, a valve structure depending from and permanently communicating 70 with said sleeve, an imperforate annular liner attached to and depending from the lower end of said body, normally communicating with said sleeve and adapted to be closed to the latter by said structure on back flow of a cementing medium, a perforated annular liner attached to and 75

extending upwardly from the upper end of said body, a conductor for and common to a washing and a cementing medium for selectively supplying said mediums to the sleeve, and said conductor and sleeve having coating means for detachably connecting them together at the other end of the sleeve, said conductor when detached from the sleeve providing for supplying the cleaning medium to the perforated liner. 5

2. In an oil well, washing and cementing apparatus, a controllable directing unit common to a washing medium and a cementing medium and adapted to be anchored in the lower portion of the well by the cementing medium applied to the bottom of the well and to the water stratum, said unit including an upper perforated annular liner, a lower imperforate annular liner, an upstanding annular coupling element interposed between and connecting said liners together, said element being formed intermediate its ends with an axially apertured horizontally disposed web constituting an abutment provided with means registering with the aperture for detachably connecting to said element a conductor common to washing and cementing mediums, and means depending from the web and communicating with said aperture to prevent back flow of the cementing medium completely through said element. 10 15 20 25

3. In an oil well washing and cementing apparatus, a controllable directing unit common to a washing medium and a cementing medium and adapted to be anchored in the lower portion of the well by the cementing medium applied to the bottom of the well and to the water stratum, said unit including an upper perforated annular liner, 30 a lower imperforate annular liner, an upstanding annular coupling element interposed between and connecting said liners together, said element being formed intermediate its ends with an axially apertured horizontally disposed web constituting an abutment provided with means registering with the aperture for detachably connecting to said element a conductor common to washing and cementing mediums, and means depending from the web and communicating with said aperture to prevent back flow of the cementing medium completely through said element, said liners 35 40 45 being all of like diameter and of less diameter than said element.

4. In an oil well washing and cementing apparatus, a controllable directing unit common to a washing medium and a cementing medium and adapted to be anchored in the lower portion of the well by the cementing medium applied to the bottom of the well and to the water stratum, said unit including an upper perforated annular liner, a lower imperforate annular liner, an upstanding annular coupling element interposed between and connecting said liners together, said element being formed intermediate its ends with an axially apertured horizontally disposed web constituting an abutment provided with means registering with the aperture for detachably connecting to said element a conductor common to washing and cementing mediums, and means depending from the web and communicating with said aperture to prevent back flow of the cementing medium completely through said element, the said means for preventing back flow being disposed in coaxial relation with respect to said element. 50 55 60 65 70

5. In an oil well washing and cementing apparatus, a controllable directing unit common to a washing medium and a cementing medium and adapted to be anchored in the lower portion of the well by the cementing medium applied to the bot- 75

tom of the well and to the water stratum, said unit including an upper perforated annular liner, a lower imperforate annular liner, an upstanding annular coupling element interposed between and connecting said liners together, said element being formed intermediate its ends with a horizontally disposed axially apertured abutment, means depending from said abutment to prevent back flow of the cementing medium completely through said element, said means being disposed in coaxial relation with respect to said element, and means detachably connected to said abutment for selectively supplying the washing medium and the cementing medium to said lower liner and for selectively supplying the washing medium to said upper liner.

6. In an oil well washing and cementing apparatus a unit common to and for the selective passage therethrough of a washing medium and a cementing medium, said unit including an upper tubular liner open at each end, a lower tubular liner open at each end and a coupling element interposed between and connected to adjacent aligned terminal portions of said liners for coupling them together, said element being formed interiorly thereof with valve means to prevent the backing up therethrough of the cementing medium.

7. In an oil well washing and cementing apparatus a unit common to and for the selective passage therethrough of a washing medium and a cementing medium, said unit including an upper tubular liner open at each end, a lower tubular liner open at each end and an upstanding coupling element interposed between and having inserted therein and connected thereto aligned terminal portions of said liners for coupling them together, said element, intermediate its ends being formed interiorly thereof with valve means to

prevent the backing up of the cementing medium into its upper portion, a conductor for selectively supplying a washing medium and a cementing to said element, said conductor and element having coating means for detachably connecting the conductor to the element, said conductor when connected to said element being extended into said upper liner.

8. In an oil well washing and cementing apparatus a unit common to and for the selective passage therethrough of a washing medium and a cementing medium, said unit including an upper tubular liner open at each end, a lower tubular liner open at each end and an upstanding coupling element interposed between and having extending therein aligned and terminal portions of said liners for coupling them together, said element, intermediate its ends being formed interiorly thereof with valve means to prevent the backing up of the cementing medium into its upper portion, the bodies of said liners being solid throughout.

9. In an oil well washing and cementing apparatus a unit common to and for the selective passage therethrough of a washing medium and a cementing medium, said unit including an upper tubular liner open at each end, a lower tubular liner open at each end and an upstanding coupling element interposed between and having inserted therein and connected thereto aligned terminal portions of said liners for coupling them together, said element, intermediate its ends being formed interiorly thereof with valve means to prevent the backing up of the cementing medium into its upper portion, the body of said lower liner being solid throughout, and the body of said upper liner being formed with spaced perforations.

JAMES E. TERRILL.
